UNITED STATES PATENT OFFICE.

JOHN H. SWAGER AND JACOB F. FERCHEN, OF ASTORIA, OREGON.

WATER-HEATER.

SPECIFICATION forming part of Letters Patent No. 352,896, dated November 16, 1886.

Application filed December 19, 1885. Serial No. 186,200. (No model.)

To all whom it may concern:

Be it known that we, JOHN H. SWAGER and JACOB F. FERCHEN, of Astoria, in the county of Clatsop and State of Oregon, have invented 5 a new and Improved Water-Heater, of which the following is a full, clear, and exact description.

Our invention is an improvement in the construction of a heater arranged to be fitted upon 10 the ordinary form of cook-stove in the place of the lower section of pipe; and it consists of one or more annular chambers arranged in connection with a water-supply tank, and of certain novel arrangements of stop-cocks and 15 faucets, as will be hereinafter explained, and specifically pointed out in the claims.

Reference is to be had to the accompanying drawings, forming part of this specification, in which similar letters of reference indicate 20 corresponding parts in both the figures.

Figure 1 is a vertical sectional elevation of our improved heater, and Fig. 2 is a sectional plan view of the same, taken on line $x-x$ of Fig. 1.

25 The apparatus illustrated in the drawings above referred to consists of an outer annular chamber, A, formed from two concentrically-arranged leaves of sheet metal, the upper and lower edges of which are united to form an 30 air and water tight annular chamber, the inner chamber, B, being formed in substantially the same way, and connected to the outer chamber by a neck, C. The inner chamber, however, does not extend as far down as the outer 35 one, the idea being to so construct the heater that it may be fitted upon the coupling-flange D to the ordinary form of range and stove.

This heater is connected to a water-supply tank, E, by an induction-pipe, F, and an education-pipe, G, the pipe F being provided with 40 a petcock, H, located at the lowest point of the pipe F, so that in cold weather the water

may be turned off from the tank and heater, while the pipe G is provided with a three-way faucet, I, each of the pipes being provided with 45 a stop-cock, as J J', which stop-cocks are located close to the tank E. The stove-pipe proper is fitted upon an upwardly-projecting flange, K, which extends from the section A, and is provided with the usual form of damper, L, 50 and also with an opening, M, which is closed by a slide or door, the idea being to permit parties using the heater to get at the inner chamber without removing the apparatus from the stove.

55 In operation the water takes the course indicated by the arrows, so that it will be readily understood that immediately after the lighting of the fire hot water may be drawn from the faucet I.

This heater does not interfere with the draft of the stove to which it is attached, requires no extra fuel, and does not in the least interfere with the ordinary culinary operations.

Having thus fully described our invention, 60 what we claim as new, and desire to secure by Letters Patent, is—

1. In a water-heater, the combination, with the chamber A and the annular chamber B, connected by a neck, C, of the pipes F and G, 70 tank E, and faucet I, substantially as described.

2. In a water-heater, the combination, with chamber A and the annular chamber B, connected by the neck C, of the pipe G, having 75 faucet I and stop-cock J, the pipe F, having cocks H and J', and tank E, substantially as described.

JOHN H. SWAGER.
JACOB F. FERCHEN.
